JACOB A. MOLLER AND ABBOTT B. JENKS, OF SANTA FE SPRINGS, CALIFORNIA.

GEARING FOR WELL-PUMPING MECHANISM.

Application filed February 24, 1925. Serial No. 11,105.

It is the object of this invention to develop any desired power at the crank which actuates the walking-beam of a well pumping mechanism, and to rotate the crank at any desired speed, without changing the speed or power of either the band wheel shaft which turns the crank or the engine which drives the band wheel shaft.

In the present practice the necessary increase of power for turning the walking-beam crank when it is adjusted for a long stroke of the pump mechanism, is developed either by speeding up the engine which drives the mechanism, or by placing a counter-shaft in the driving connection between the engine and the band wheel shaft on which the crank is mounted.

The first of these methods requires running of the engine at excessive speed to develop the necessary power; and the second method changes the rotary speed of the band wheel shaft, so that when the band wheel is used for pulling the well, it will not operate at an efficient speed until the counter-shaft has been removed from the driving connection.

Our invention contemplates the provision of means for changing the speed and power ratio between the band wheel shaft and the walking-beam of a well pumping apparatus. For this purpose reduction gearing is preferably provided between the band wheel shaft and the crank which operates the walking-beam, so that by changing the ratio of the gearing, the crank may be turned at any desired speed and will develop any required power, without changing the speed of the band wheel shaft or the engine which drives the same.

The stroke of the pump mechanism may thus be adjusted without necessitating a change of the engine speed or reduction in the speed of rotation of the band wheel shaft, so that a relatively long stroke may be employed at relatively slow speed.

The invention will be readily understood from the following description of the accompanying drawings, in which:

Fig. 1 is a side elevation of a well rig showing the reduction gearing.

Fig. 2 is a front elevation of the reduction gearing.

Fig. 3 is a side elevation of the same.

Fig. 4 is a vertical section through the gearing.

A practical embodiment of the invention is

illustrated as employed in connection with a standard well rig including the derrick floor 1 on which the derrick 2 is mounted. The string of sucker rods 3 in the well tubing 4 are reciprocated to operate the pump mechanism by walking-beam 5 mounted on Sanson post 6. The walking-beam is operated by the band wheel shaft 7 which is journaled on jack posts 8, and operatively connected to the walking-beam by pitman 9 and crank 10. The band wheel 11 which is keyed on shaft 7 is driven by the engine 12 through the belt 13. The bearings for shaft 7 comprise cooperating half-bearings 14, connected by bolts 15 and fixed on the jack posts by bolts 16 and turnbuckle braces 17.

The improved driving connection is provided between shaft 7 and crank 10, so that any desired speed or power may be developed at the crank, with shaft 7 and engine 12 running at constant speed. For this purpose reduction gearing is mounted on shaft 7 and on a counter-shaft 18 having the crank fixed thereto.

The counter-shaft is journaled in cooperating half-bearings 19, which are preferably mounted on the bearing 14 at the end of shaft 7 which is adapted to rotate crank 10. Bearings 14-19 may be alined by a tongue and groove connection 20 between the same; and the halves of bearing 19 are connected, and said bearing is fixed relative to bearing 14 and jack post 8, by extending bolts 15 and 16 through the halves of bearing 19, with nuts 21 on said bolts impinging against both bearing blocks 14 and 19. The bearing 19 may be further braced by turnbuckle braces 17.

Gears 22 are mounted on the ends of shaft 18 and mesh with gears 23 on the shaft 7, the gears being keyed to their shafts as shown at 24 so that they may be readily removed and replaced in order to obtain any desired gear ratio. The outer end of shaft 18 projects beyond the outer gear 22 so that crank 10 may be fixed thereon, the crank being preferably fixed for rotation with the counter-shaft by the same key 24 that holds the gear 22.

The crank is of usual construction including the strengthening rib 25 having a plurality of apertures 26 extending therethrough and spaced lengthwise of the crank. A usual wrist-pin 27 on which the end of pitman 9 is journaled, is received through any one of the apertures 26 and fixed in

place by a nut 28, so that by changing the wrist-pin to different apertures the stroke of the walking-beam 5 may be varied as desired.

5. Rotation of shaft 7 is thus adapted to turn crank 10 through the meshing gears 22-23, the crank in turn operating the walking-beam through the pitman 9. The mounting of gears 22-23 at both ends of 10 the bearings 14-19 balances the construction and eliminates vibration, and also provides a strong and durable driving connection.

By changing the gears 22-23 any desired 15 gear ratio may be obtained in order to turn crank 10 at any desired speed and with any required power development, without changing the speed of engine 12 or the band wheel shaft 7.

The increased power necessary for turning 20 the crank when wrist-pin 27 is set for a long stroke of the walking-beam, may thus be obtained without speeding up the engine; and by providing for change of the speed or power of the crank without changing 25 the driving connection for the band wheel shaft, the band wheel is immediately available for operation at maximum efficiency when pulling the well.

We claim:

30 1. An operating connection for well pumping apparatus, comprising a jack post,

a bearing mounted thereon, a band wheel shaft journaled in said bearing, a bearing mounted on said first bearing, a counter-shaft journaled in the second bearing and 35 having the crank of the pumping apparatus fixed on said counter-shaft, and gearing between the counter-shaft and the band wheel shaft.

2. An operating connection for well 40 pumping apparatus, comprising a jack post, a bearing mounted thereon, a band wheel shaft journaled in said bearing, a bearing mounted on said first bearing, means for fixing said bearings relative to one another 45 and the jack post, a counter-shaft journaled in the second bearing and having the crank of the pumping apparatus fixed on said counter-shaft, and gearing between the counter-shaft and the band wheel shaft. 50

3. An operating connection for well pumping apparatus comprising a jack post, a bearing mounted thereon, a drive shaft journaled in said bearing, a second bearing mounted on the first bearing, a counter-shaft journaled in the second bearing, 55 means for driving the well pumping apparatus by said counter-shaft, and an operating connection between the drive shaft and said counter-shaft.
